UNITED STATES PATENT OFFICE.

WILLIAM H. MARTIN, OF DETROIT, MICHIGAN.

HOUSE MAIL-RECEPTACLE.

1,359,412.

Specification of Letters Patent. Patented Nov. 16, 1920.

Application filed March 31, 1920. Serial No. 370,127.

To all whom it may concern:

Be it known that I, WILLIAM H. MARTIN, a citizen of the United States, residing at Detroit, in the county of Wayne and State 5 of Michigan, have invented certain new and useful Improvements in House Mail-Receptacles, of which the following is a specification.

This invention relates to mail boxes and 10 has for an object to provide a mail box having separate compartments for receiving and retaining mail matter of different classes with improved means for positioning the mail box conveniently accessible to the mail 15 carrier.

Further object of the invention is to provide a mail box having a compartment properly proportioned to receive mail and other packages of large size, with a closure for 20 such compartment and an auxiliary compartment, having a communicating slot for receiving mail matter of small size, with a closure for the auxiliary compartment opening into the larger compartment and 25 controlled by a lock positioned within the larger compartment.

With these and other objects in view the invention comprises certain novel units, structures, combinations and functions as 30 will be hereinafter more fully described and claimed.

In the drawings,

Figure 1 is a view in perspective of one type of the improved mail box with one 35 type of support.

Fig. 2 is a vertical sectional view taken on the lesser diameter as indicated by line 2-2 of Fig. 1.

Fig. 3 is a transverse horizontal section 40 taken on line 3-3 of Figs. 1 and 2.

Fig. 4 is a perspective view of a different type of mail box, embodying the same inventive concept but different in shape and showing a different type of support.

Fig. 5 is a vertical sectional view taken 45 on line 5-5 of Fig. 4.

Fig. 6 is a vertical sectional view at right angles to the plane of Fig. 5 and taken on line 6-6 of Fig. 4.

Like characters of reference indicate 50 corresponding parts throughout the several views.

The improved mail box, which forms the subject matter of this application, may be 55 made of various shapes and designs but comprises a body portion 10 as indicated

at Fig. 1 or 11 as indicated at Fig. 4. The mail box is closed at the top in such manner as to prevent the access of water thereto by a cover member 12 having overhanging 60 and downwardly extending eaves 13. At the front a large door or closure 14 is provided, having a latch 15 communicating with the larger interior compartment 16. It is not the intent to lock the door 14 but 65 to have it retained in closed position only by the manual latch permitting the opening of such door for the deposit of large mail matter, parcels, packages, newspapers and the like. The second compartment 17 70 is provided by a partition 18 having a letter slot 19 for the insertion of letters into the compartment 17. The partition 18 is provided with a hinged closure 20 having a lock 21 accessible only from within the compartment 16. 75

The device, so constructed, is mounted in any approved manner, depending upon the required location a tripod 22 being shown at Figs. 1, 2 and 3, the lower extremities 80 of the legs being pointed for insertion into the ground. At Fig. 4 a post 23 is shown likewise pointed and it is the intent that either of these supports should be mounted upon the lawn or in other position adjacent 85 the route of the letter carrier making it unnecessary for the carrier to travel from the highway to the door of the recipient. At Figs. 5 and 6 posts 24 are shown and such posts may be the equivalent of the post 90 23 or may be the post of a porch or other permanent structure easily available to the carrier.

It is well known that letter carriers employ a large portion of their time traveling from the sidewalk or other highway to the doors of the recipient and waiting the coming of the recipient in answer to rings at the door bell or other alarms. It is also well known that house deliveries of city 100 newspapers are made, under many circumstances, by throwing the paper on to the lawn or the porch or the steps where it is subject to be carried away by the wind or being reduced to pulp by rain falling 105 thereon. With the use of the device of the present application not only mail matter may be conveniently deposited with minimum loss of time but newspapers and other matters, which are delivered at residences, 110 may likewise be deposited within the compartment 16 without danger from the ele-

ments and with a minimum of labor. While the device is especially intended for mail matter, daily newspapers and the like it is obviously not limited to such articles and 5 may be a receptacle for any article that is to be delivered at the address.

A signaling device 25 adapted to be turned to upright position when things are placed in the receptacle and thrown down 10 when they are removed is preferably mounted in any appropriate manner on the top of the device, as shown. The cover 12 is also preferably hinged, as at 26, to enable the mail or other articles to be deposited therein from the top when more 15 convenient than through door 14. The compartment 17 is too narrow for the hand to be inserted from the top to remove its contents, and may be partially closed at the 20 top, as indicated at Fig. 5 to more securely guard its contents.

It will be understood that these receptacles may be attached to a fence post, a porch post or be supported on independent 25 posts or legs, as shown in the drawings. Such posts or legs when specially designed as a part of the device are formed pointed so that they may be inserted in the parking or lawn alongside of the walk or curb to 30 bring the box to the position which will be the most desirable and convenient for the purpose.

Having thus fully described my said invention what I claim as new and desire to 35 secure by Letters Patent, is:

1. A deposit receptacle for mail, etc., comprising, a housing divided by a vertical partition into a larger compartment for receiving large packages and a smaller compartment for receiving letter mail or like 40 small packages, said housing having a perforation permitting the introduction of

small packages into the smaller compartment from without and an opening in the side thereof permitting access to the larger 45 compartment from without, a closure for the opening, said partition provided with an opening and a hinged closure therefor whereby access is had to the smaller compartment only within the larger compartment, a lock for the last mentioned closure, and a hinged cover forming the top of the receptacle and permitting access to the larger compartment only.

2. A deposit receptacle for mail, etc., 55 comprising, a housing divided by a vertical partition into a larger compartment for receiving large packages and a smaller compartment for receiving letter mail or like small packages, said housing having a 60 perforation permitting the introduction of small packages into the smaller compartment from without and an opening in the side thereof permitting access to the larger compartment from without, a closure for the 65 opening, said partition provided with an opening and a hinged closure therefor whereby access is had to the smaller compartment only within the larger compartment, a lock for the last mentioned closure, 70 a hinged cover forming the top of the receptacle and permitting access to the larger compartment, and a fixed cover beneath the said hinged cover forming a closure for the smaller receptacles to prevent access thereto 75 from the top.

In witness whereof I have hereunto set my hand and seal at Detroit, Michigan, this 29th day of March, A. D. nineteen hundred and twenty.

WILLIAM H. MARTIN. [L. S.]

Witnesses:

PHILIP E. GRENIER,
F. L. STURDEVANT.
